(57) CLAIM

The ornamental design for a fishing lure, as shown and described.

DESCRIPTION

FIG. 1 is a top, front perspective view of a fishing lure, showing my new design;

FIG. 2 is a right elevation view thereof, the left elevation view being a mirror image thereof;

FIG. 3 is a top plan view thereof;

FIG. 4 is a bottom plan view thereof;

FIG. 5 is a front elevation view thereof; and,

FIG. 6 is a rear elevation view thereof.

The broken lines shown in the drawings depict portions of the fishing lure that form no part of the claimed design.
